UNITED STATES PATENT OFFICE.

HIRAM E. GREEN, OF LOWELL, MASSACHUSETTS.

EDGE-UNFOLDER FOR FABRIC-PRINTING OR OTHER MACHINES.

SPECIFICATION forming part of Letters Patent No. 739,781, dated September 22, 1903.

Application filed November 9, 1897. Serial No. 657,925. (No model.)

To all whom it may concern:

Be it known that I, HIRAM E. GREEN, a citizen of the United States, residing at Lowell, in the county of Middlesex and Commonwealth of Massachusetts, have invented a certain new and useful Improvement in Edge-Unfolders for Fabric-Printing, Cloth-Drying, Calendering, or other Machines, of which the following is a specification.

This invention relates to edge-unfolders for fabric-printing, cloth-drying, calendering, and other machines, the object of which is to treat one face of cloth or similar sheet material uniformly from edge to edge. In all such machines the sheet is liable to be turned over at the edge and to be pressed down flat in such a manner that the face of the cloth intended to be operated upon is protected from the operation of the proper rolls for a distance twice as wide as the fold and the reverse face of the cloth is acted upon for the width of the fold. Thus in calico-printing in printing figures upon a white or other ground a turned or "doubled" edge will prevent the color from being applied to the inside of the folded part. In a cloth-drying machine a double edge will prevent the uniform drying of the cloth, the folded part retaining the moisture. In calendering, a double edge will prevent a uniform smoothing or glazing of the cloth from selvage to selvage.

The object of this invention is to unfold the folded edge or double edge of the fabric and by laying the fabric flat to expose its proper face to the desired action of the machine.

In the accompanying drawings, Figure 1 is a right-side elevation of such parts of a calico-printing machine as is necessary to the explanation of this invention, showing the edge-unfolders in operative position; Fig. 2, a rear elevation of the same; Fig. 3, a plan of an edge-unfolder and a part of its supporting-bracket.

A represents the frame; B, the main cylinder; C, the traverse-roll—all being of the usual construction and operation, and the main cylinder being driven by the usual means and driving, through the gears b d and the vertical shaft D, the rolls (not shown) which take away the cloth E and blanket F from the machine.

The engraved printing-rolls H H' (shown in dotted lines in Fig. 1) are arranged at intervals to press upon the cloth below the middle of the main cylinder in the usual manner, and the unfolding devices are arranged to act upon the cloth E before it reaches the printing-rolls.

The direction of the cloth which passes over the traverse-roll C and under the main cylinder B is indicated by arrows.

The edge-unfolder, Fig. 3, consists of a cylindrical roll G, provided with projections or bosses g, arranged helically on said roll and conveniently made by cutting in the curved surface of said roll one or more helical grooves g' or screw-threads and a sufficient number of flutes or longitudinal grooves g², crossing said helical groove or grooves g'. The drawing Fig. 3 represents the roll G as being provided with a multiplex thread of bosses in order to give a greater pitch to the thread without making the bosses too coarse. In no case must the bosses be fine enough or pointed enough to pierce the cloth or other sheet material; but the outer ends of the bosses should be blunt and at nearly right angles to the sides of the bosses. The roll G turns freely on an arbor g³, on which it is retained in any usual manner, as by a spring split pin g⁴, which passes through the free end of said arbor and holds the opposite end of said roll against a collar g⁵ on said arbor and prevents any endwise motion of said roll on said arbor. The other end of the arbor g³ is loosely pivoted at g⁶ in a bracket g⁷, adapted to be secured to the frame A by washers g⁸ and bolts g⁹, which pass through said washers and through a slot g¹⁰ in said bracket, said slot g¹⁰ being long enough to allow of an adjustment of the pivoted end of the arbor toward and away from the center of the main cylinder B, as shown in Figs. 1 and 2, to vary the position of said roll G according to the size of said cylinder. The pivoting of the arbor g³ to the bracket g⁷ enables the roll G to be turned out of contact with the sheet material or into contact with the same and to be held in either of these positions by its own weight, as shown in Fig. 3, where the position of the roll when out of contact with the sheet material is indicated by dotted lines.

The roll G is represented as having a right-

hand thread and would be placed to bear upon the cloth on the traverse-roll C at the left of Fig. 2—that is, at the right of the machine—while a similar roll G', having a left-handed thread, would be placed at the other end of said traverse-roll and would rest upon the cloth, so that the cloth passing between said embossed rolls G G' and the traverse-roll would rotate said embossed rolls. The rotation of said embossed rolls will cause their helically-arranged bosses to catch and move outward the selvages of any folds on the back of the cloth, opening said folds and smoothing the cloth, and such bosses will perform their office much more efficiently than a continuous smooth helix or screw-thread, because the leading outer corner of each boss will be capable of acting upon a folded edge and will engage an edge that a continuous thread might slip over. These rolls G G' are preferably arranged at an obtuse angle with the approaching selvage of the cloth to increase the lead of the helical threads of bosses.

25 To prevent the cloth from being cut between the bosses and the traverse-roll, (the latter being a metallic roll without soft covering,) the free ends of the rolls G G' are provided with a covering g^{11} of slightly larger 30 outside diameter than the outside diameter of the metallic part of said rolls G G', the free ends of each of said rolls being reduced, as indicated by dotted lines at g^{12} in Fig. 3, and covered with a ring g^{11} , preferably of leather; which is retained on said roll by cement or by a washer g^{13} , of greater diameter than the reduced part g^{12} of said roll and smaller than the outside diameter of said ring, said washer being held against the free end 35 of the body of the roll by the split pin g^4 , above mentioned. Other embossed rolls G G' remove folds from the front or outer face of the cloth, said rolls being placed to rest upon the cloth while the same is running upon the 40 main cylinder B, these last-named rolls being similar to the embossed rolls which rest on the traverse-roll and being operated and arranged with reference to the approaching selvages of the cloth, as above described, the 45 only difference being that as the main cylinder is covered by a pad of felting or other soft material and by the blanket F the annular cushion or covering g^{11} is omitted from the lower pair of embossed rolls.

50 55 I claim as my invention—

1. An edge-unfolder, consisting of a roll, provided with one or more series of helically-

arranged bosses, and adapted to rest upon a sheet material and to be rotated by the movement thereof, said bosses having smooth, 60 blunt outer ends.

2. An edge-unfolder, consisting of a cylindrical roll, having its curved surface provided with longitudinal grooves and with one or more spiral grooves dividing said surface 65 into angular bosses having smooth blunt outer ends.

3. An edge-unfolder, consisting of a cylindrical roll, having its curved surface provided with longitudinal grooves and with one 70 or more spiral grooves dividing said surface into angular bosses, having smooth blunt outer end surfaces concentric with said roll.

4. An edge-unfolder, consisting of a roll, provided with one or more series of helically- 75 arranged bosses, and adapted to rest upon a sheet material and to be rotated by the movement thereof, said roll being also provided with a ring having a greater diameter than the outside diameter of said roll including 80 said bosses.

5. An edge-unfolder, consisting of a roll, provided with one or more series of helically-arranged bosses, and adapted to rest upon a sheet material and to be rotated by the movement thereof, said roll being also provided with a ring or annular cushion of soft material, having a greater diameter than the outside diameter of said roll including 85 said bosses.

6. The combination of a roll, provided with one or more series of helically-arranged bosses, and a roll, or cylinder, adapted to feed sheet material arranged in contact with said bosses and between said rolls.

7. The combination with the frame and main cylinder, of a bracket, supported on said frame, an arbor, loosely pivoted to said bracket, a roll, turning on said arbor and provided with one or more series of bosses, arranged in helical rows on said roll, said roll being adapted by turning said arbor on its pivot to be brought into or out of contact with sheet material carried by said cylinder and to be held by its own weight in either of 100 105 said positions.

In witness whereof I have signed this specification, in the presence of two attesting witnesses, this 25th day of October, A. D. 1897.

HIRAM E. GREEN.
